United States Patent

Des. 235,690
Patented July 1, 1975

235,690

HANDBAG

Valerie Barad, Gardena, Calif., assignor to Theodor
Manufacturing Corp., Gardena, Calif.

Filed June 11, 1973, Ser. No. 368,616

Term of patent 14 years

Int. Cl. D3—01

U.S. Cl. D87—3 F

FIG. 1 is a front perspective view of a handbag, showing my new design;

FIG. 2 is a left side elevational view;

FIG. 3 is a top plan view;

FIG. 4 is a rear elevational view;

FIG. 5 is a bottom plan view; and

FIG. 6 is a fragmentary right side elevational view, the top and a portion of the strap being broken away for convenience of illustration.

I claim:

The design for a handbag, substantially as shown and described.
